UNITED STATES PATENT OFFICE.

JAMES E. SHOPE, OF DUNBAR, PENNSYLVANIA.

RAIL-CHAIR.

SPECIFICATION forming part of Letters Patent No. 588,360, dated August 17, 1897.

Application filed April 12, 1897. Serial No. 631,785. (No model.)

To all whom it may concern:

Be it known that I, JAMES E. SHOPE, a citizen of the United States, residing at Dunbar, in the county of Fayette and State of Pennsylvania, have invented certain new and useful Improvements in Rail-Chairs; and I do declare the following to be a full, clear, and exact description of the invention, such as will enable others skilled in the art to which it appertains to make and use the same.

My invention has relation to a rail-chair for railways, and the object is to provide a chair which shall be simple of construction, durable in use, and one by the employment of which the ordinary bolts and fish-plates used for joining the abutting ends of rails are dispensed with and the rails securely held in alignment and against spreading.

With this object in view the invention consists of certain features of construction and combination of parts, which will be hereinafter fully set forth and claimed.

In the accompanying drawings, Figure 1 is a plan view looking down upon the abutting ends of two rails and illustrating the application of my invention thereto. Fig. 2 is a longitudinal sectional view through the line *x x* of Fig. 1; and Fig. 3, a sectional view on line *y y*, Fig. 1.

In the drawings, 1 denotes the ties or sleepers, and 2 the abutting ends of two rails.

3 denotes my improved chair, which consists of a casting provided with tie-securing arms 4, an upwardly-projecting web-embracing head 5, provided with pins 5^a, and a horizontal base 6, which projects under the base of the rails and supports the same and is provided with an aperture 7 and a cross-head 7', having a perforated boss 7^a. A chair thus constructed is cast in one integral piece.

9 denotes a clamping-plate which is adapted to lie against the outer side of the webs of the rails and is provided with holes 10, through which and the abutting ends of the rails the pins 5^a of the web-embracing head project. This plate has an integral arm extending in

an inclined direction through the hole 7 in the base of the chair and is provided with a hole 11, through which passes the lower end of a bolt 12, which projects upwardly through 50 the boss 7^a of the cross-head 7' and receives upon its end a drawing-nut 13.

The arms of the cross-head of the chair are securely spiked to the ties or sleepers. By adjusting the nut 13 the lower inclined end of 55 the clamping-plate will be drawn outwardly, thus forcing the clamping-plate firmly against the abutting ends of the rails and securely locking them in position against displacement caused by the vibration incident to a 60 passing train.

Although I have specifically described the construction and relative arrangement of the several elements of my invention, I do not desire to be confined to the same, as such 65 changes or modifications may be made as clearly fall within the scope of my invention without departing from the spirit thereof.

Having thus described my invention, what I claim, and desire to secure by Letters Patent, is—

A chair for railway-rails, comprising in combination, arms adapted to be spiked to the ties, and provided with an upwardly-extending web-embracing head having outwardly-projecting pins and an outwardly-projecting base adapted to support the rails, said base being provided with an opening and with a bolt-hole, and upon its upper side with a cross-head having an apertured boss, a clamping-plate having holes to receive the pins aforesaid, and an inclined arm provided with a bolt-hole and a bolt passed through the boss and the said arm, and provided with a nut for clamping the parts, substantially as 85 set forth.

In testimony whereof I hereunto affix my signature in presence of two witnesses.

J. E. SHOPE.
